UNITED STATES PATENT OFFICE.

LUDWIG DÜRR, OF FRIEDRICHSHAFEN, GERMANY, ASSIGNOR TO THE FIRM: LUFT-SCHIFFBAU ZEPPELIN, GESELLSCHAFT MIT BESCHRÄNKTER HAFTUNG, OF FRIEDRICHSHAFEN, GERMANY.

AIRSHIP.

Application filed June 28, 1920. Serial No. 392,539.

To all whom it may concern:

Be it known that I, LUDWIG DÜRR, a German citizen, residing at Friedrichshafen, Germany, have invented certain new and useful Improvements in Airships (for which I have filed an application in Germany April 8, 1918, No. 310,728), of which the following is a specification.

My invention refers to airships and more especially to airships of the rigid type comprising a plurality of gas chambers and its particular object is a novel system of stiffening the outer envelopes of the gas chambers, which will enable the transmission of the excess pressures prevailing in said gas chambers to the various portions of the framework of the airship to be effected in such a manner that said framework and, in particular, the stay wires of the cross rings will be secured against overloading.

Now in one stiffening or staying arrangement of this kind at present in use the end surfaces of the single gas chambers are anchored to one another by means of tension members extending within the interior thereof, the said members then being continued along from one chamber to the other until the ends of the rigid framework are reached. In another form of staying arrangement, the cylindrical outer faces of the gas chambers are braced relatively to the longitudinal members of the ship's frame.

Now this last mentioned method of bracing, while requiring numerous points of attachment for the gas chambers will, notwithstanding, relieve the frame of the ship inadequately. If, on the other hand, the end faces of the single chambers were to be braced by means of tension members disposed within said cells, then there would be created the liability of the points of fixation being easily ripped or torn. Moreover a free supporting tension rope carried along from point to point, on to which the single chambers are immovably suspended, will practically offer substantially no protection in the event of the rope snapping at any point.

The special object of my present invention resides in producing a bracing arrangement between the gas chambers and the ship's frame, in the case of which the end surfaces of the gas chambers are on the one hand secured against being ripped, while on the

other hand, they are prevented from exerting any admissible big strain on the centre points of the transverse tension members of the cross rings. At the same time, the through-going tensile connection is intended to be secured against overstrain, and each of the chambers of the cells located always between two ring supports shall be so stiffened as to be capable of offering an increased resistance per se.

Thus the subject matter of this invention constitutes a rigid air-ship having separate gas chambers and through-carried tension members, which latter are braced by means of the tension wires of the cross rings. In order to render possible the free and unhampered movement of the gas chambers in an axial direction, the end surfaces of said chambers are shiftably disposed relatively to the tension members by which they are traversed. This shiftability will be suitably obtained by providing the end surfaces of the gas chambers at the places entering into consideration with a central bag-like reentrant sleeve. By these means the provision of any sort of sliding sleeve joint liable to cause leakages and objectionable frictions may be successfully avoided. To facilitate the mounting, and the exchanging of single gas chambers, it will be found advantageous to divide the tension member into single sections extending always from one point of anchorage to the next, and which sections are adjustably connected by pin joints to said points of anchorage.

A structure embodying my invention is shown diagrammatically by way of example in the accompanying drawing forming part of this specification. In the drawings—

Fig. 1 is a longitudinal section of part of the frame of an air ship, and

Fig. 2 a view, partly in longitudinal section, of the point of anchorage, drawn on an enlarged scale.

The stay wires a' of each cross ring A are enclosed in the centre thereof by a two-part anchor plate B. The two plate discs, which are bolted or screwed together, support each a pin or pivot b' pivotally connected to the forked end of each of the threaded bolts c' . Each of these latter is embraced by a tightening sleeve C secured by a lock nut c^2 , into the bottom of which sleeve is fastened the end d' of the tension rope D. The end d' is provided with a collar, and firmly tied to

said end so as to be perfectly gas tight is the inner portion of a central bag like re-entrant sleeve e' of the bottom E of a gas chamber. As will be seen from the drawing, 5 the bottom of the gas chamber is enabled to repose upon the tension wires a' , secured by the tension rope D , without thereby creating any liability of rupture or break.

I claim:

- 10 1. In a rigid airship in combination, a rigid tubular frame, a plurality of gas cells surrounded by said frame, bracing wires between two gas cells meeting substantially in the centre line of said frame, a tension member extending longitudinally through said frame and said cells and fixed to said bracing wires and short axially extending sleeves connected with the cell walls traversed by said tension member and loosely but closely fitting around said member.
- 15 2. In a rigid airship in combination, a rigid tubular frame, a plurality of gas cells

surrounded by said frame, bracing wires between two gas cells meeting substantially in the centre line of said frame, a tension member extending longitudinally through said frame and said cells and fixed to said bracing wires and short reentrant sleeves connected with the cell walls traversed by said tension member and loosely but closely fitting around said member. 25 30

3. In a rigid airship in combination, a rigid tubular frame, a plurality of gas cells surrounded by said frame, bracing wires between two gas cells meeting substantially in the centre line of said frame, a tension member extending longitudinally through the parallel walls of each cell and having its ends fixed to said wires and a short reentrant sleeve in each wall loosely but closely fitting around said tension member. 35 40

In testimony whereof I affix my signature.

LUDWIG DÜRR.
